DESIGN FOR A COMBINED STERILIZING AND IMPLEMENT HOLDING CABINET

Carell A. Newland, Kansas City, Mo.

Application June 20, 1938, Serial No. 77,948

Term of patent 3½ years

To all whom it may concern:

Be it known that I, Carell A. Newland, a citizen of the United States of America and resident of Kansas City, in the county of Jackson and State of Missouri, have invented a new, original, and ornamental Design for a Combined Sterilizing and Implement Holding Cabinet, of which the following is a specification, reference being had to the accompanying drawing, forming part thereof, in which, Fig. 1 is a front perspective

view of the article, showing my new design, with some of the parts shown in the open position. Fig. 2 is a front elevational view. Fig. 3 is a top plan view. Fig. 4 is a reduced scale rear elevational view.

I claim:

The ornamental design for a combined sterilizing and implement holding cabinet, as shown.

CARELL A. NEWLAND.
